UNITED STATES PATENT OFFICE.

GEORGE ALBERT SWINEFORD, OF CANTON, OHIO.

DOOR-HANGER.

No. 909,036.

Specification of Letters Patent.

Patented Jan. 5, 1909.

Application filed March 9, 1907. Serial No. 361,445.

To all whom it may concern:

Be it known that I, GEORGE ALBERT SWINEFORD, a citizen of the United States, residing at Canton, in the county of Stark and State 5 of Ohio, have invented an Improvement in Door-Hangers, of which the following is a specification.

This invention relates to hinged hangers for use in suspending a door on a track; and 10 the objects of the invention are to provide a hanger which can be easily assembled on or off the track, and when connected with the door can be easily and readily placed on and removed from the track from the side thereof, and when on the track will be guarded 15 against being accidentally removed therefrom. These general objects and other minor ones relating to details are attained by the construction and arrangement illustrated in the accompanying drawings, in 20 which—

Figure 1 is a fragmentary view of a piece of track and sections of two doors, one of 25 which is suspended vertically and the other swung outward on the hinge pivot; Fig. 2, a side elevation of one hanger located on a section of track; Fig. 3, a vertical section on line 3—3, Fig. 2; Fig. 4, a perspective view 30 of the several parts of the hanger separated from their assembled position; and Fig. 5, a detached perspective view of an alternate form of the yoke.

Similar numerals refer to similar parts 35 throughout the drawings.

The track 1 may be of the usual type and is preferably formed of a vertically disposed flat bar which may be attached on the side of a building above the door opening (not shown) by means of the T-shaped bracket 40 2, the stem of which is connected with the middle part of the track bar, thus leaving the edges, the outer side, and the upper and lower parts of the inner side of the track bar free from any obstruction.

The track member of the hanger is preferably composed of the frame or hood 3 in which the vertically disposed roller 4 is journaled. The roller is provided with the 45 peripheral groove 5, which is adapted to engage over and to travel on the upper edge of the track bar. These features of construction may be of any ordinary and well-known form and do not comprise any part of the present invention.

The straps 6, of which there are prefer-

ably two, one being located at each end of the hood, depend from the outer side of the hood, and on the lower ends of these straps are formed or attached the bearings 7 for the pivot-pins 8, the straps being bent or inclined so that these bearings are located directly under the track bar when the roller is mounted thereon, as shown more particularly in Fig. 3.

The yokes 9 are suspended from the hanger bearings by means of the pivot-pins, the same being passed through the journal apertures 10 in the arms of the yokes, and the hanger bearings. Each pivot-pin is preferably provided with a head 11 on one end, and when inserted through the hanger bearing and the yoke-arms, are conveniently held in place by the ordinary key 12 inserted through the aperture 13 in the protruding part of the other end. The yokes are preferably secured to the door by means of the U-shaped straps 14, as shown, which straps are adapted to be fastened to the door by means of the bolts 15 passed through the apertures 16 in the branches of the strap and 80 into and, if necessary through, the door. The upper ends of the said branches are bent over the upper edge of the door 17 and thence downward along the other side thereof, thus forming the loop or bail 18 which is 85 engaged over the horizontal bar 19 of the yoke 9; and the downwardly extending portions 20 of the door straps may be provided with the apertures 16' through which the bolts 15 may also be passed, thus firmly securing the bail formed straps to the door.

It is evident that by fastening the yokes against the upper edge of the door by means of the strap bails, as shown in Fig. 1, the yokes are rigidly fastened to the door, and 90 that the yokes and straps together comprise two-piece door members of the hangers; and it is also evident that the yokes can be formed integral with the straps, if desired, as shown in Fig. 5, thus forming one-piece 100 door members, but the separate yokes and straps are preferred for convenience and economy in manufacture.

The upper and outer edges 21 of the arms of the yokes are curved so that when the parts are assembled said curved portions will be located adjacent to the lower edge of the track bar, and on the inner parts of the arms of the yokes are provided the fingers 22 which normally extend upward 110

and in rear of the lower part of the track bar. The upper edges of the yoke-arms being adjacent to the lower edge of the track bar and the yoke-fingers being extended behind the track bar, it is impossible for the wheel to be raised sufficiently to jump the track; and furthermore it is impossible for the hanger bearings and the yokes to be swung outward so that the rollers can be lifted from the track. But, by swinging the door outward on the pivot-pins, as shown at 17' in Fig. 1, the yoke-fingers, being fixed on the door members, are rotated downwardly far enough to clear the lower edge of the track bar, whereupon the hanger bearings and the yokes are free to be moved outward to clear the track bar, and the rollers can be readily lifted off the track. It is also evident that the track member and the door member of the hanger can be assembled or taken apart by merely inserting or removing the pivot-pin.

What I claim as my invention, and desire to secure by Letters Patent, is—

25 1. A hanger for suspending a sliding-door on a track-bar comprising a hood having a grooved-roller journaled therein adapted to engage and travel on the track-bar and having pendent-bearings located 30 under the same, yokes pivoted to the pendent-bearings having the upper portions of their sides curved and located adjacent to the track-bar and having fingers normally extending upward behind the same, and 35 straps fastened to the sides of the door and engaging the yokes.

2. A hanger for suspending a sliding-door on a track-bar comprising one member having a grooved-roller journaled therein 40 adapted to travel on the track-bar and having pendent-bearings normally located under the same, and yokes secured to the door and detachably pivoted to the pendent-bearings, the upper edges of the yokes being 45 curved and located adjacent to the track-bar and having fingers normally extending upward in rear of the same.

3. A hanger for suspending a sliding-door on a track-bar comprising one member 50 having a grooved-roller journaled therein adapted to travel on the track-bar and having a pendent-bearing normally located under the same, and another member secured to the door and detachably pivoted to the 55 pendent-bearing including an arm having its end curved and located adjacent to the

track-bar and having a finger normally extending upward in rear of the same.

4. A hanger for suspending a sliding-door on a track-bar comprising one member 60 having a grooved-roller journaled therein adapted to travel on the track-bar and having a pendent-bearing normally located under the same, and another member secured to the door and detachably pivoted to 65 the pendent-bearing and provided with an arm having its end located adjacent to the track-bar and having a finger normally extending upward in rear of the same.

5. A hanger for suspending a sliding-door on a track-bar comprising a member adapted to engage and travel on the track-bar and having a pendent-bearing normally located under the same, and another member secured to the door and detachably 75 pivoted to the pendent-bearing and provided with an arm having its end located adjacent to the track-bar and having a finger normally extending upward in rear of the same.

6. A hanger for suspending a sliding-door on a track-bar comprising one member adapted to engage and travel on the track-bar and having a pendent-bearing normally located under the same, and another member secured to the door and pivoted to the pendent-bearing and provided with an arm having its end located adjacent to the track-bar and having a finger normally extending upward in rear of the same.

7. A hanger for suspending a sliding-door on a track-bar comprising one member adapted to engage and travel on the track-bar and having a pendent-bearing normally located under the same, and another member secured to the door and detachably pivoted to the pendent-bearing and provided with a finger normally extending upward in rear of the track-bar.

8. A hanger for suspending a sliding-door on a track-bar comprising one member adapted to engage and travel on the track-bar and having a pendent-bearing normally located under the same, and another member secured to the door and pivoted to the 100 pendent-bearing and provided with a finger normally extending upward in rear of the track-bar.

GEORGE ALBERT SWINEFORD.
